ORTHOPEDIC HAND

José Antonio Quirno Costa, Buenos Aires,
ArgentinaApplication November 23, 1942, Serial No. 466,642
In Argentina September 30, 1942

2 Claims. (Cl. 3—12)

This invention relates to certain new and useful improvements in orthopedic hands and an essential object of the same consists in providing an improved hand of the said kind which will allow of performing most of the functions of a natural hand.

In order that the invention may be clearly understood and readily carried into practice, a preferred embodiment of the same has been shown, by way of example, in the accompanying 10 drawings, wherein—

Figure 1 shows a perspective of an orthopedic hand constructed in accordance with this invention.

Figure 2 is a central cross section of the wrist of 15 the hand.

Figure 3 illustrates an end view of the outer face of the wrist block shown in Figure 2.

Figure 4 shows a perspective of the same hand, 20 wherein the means for controlling the thumb may be seen.

Figure 4a is an enlarged detail perspective view of the release member for the thumb ratchet.

Figure 5 is another perspective which illustrates the means for controlling the fourth finger, the 25 other fingers having been omitted.

Figure 6 shows still another view which illustrates the retaining means for holding the fourth finger in its several positions.

Figure 6a is a detail perspective view of the 30 release member for the rack which controls the movement of the fourth finger.

Figure 7 illustrates a perspective of an orthopedic hand in accordance with this invention, provided with an additional retention or fixing means.

Similar numbers of reference have been used to 35 indicate like or corresponding parts in all the views.

The construction shown in the drawings is that of a left hand and in the following description, the 40 references correspond with such embodiment, although it will be evident that in the case of a right hand, the description and operation would be similar, only in a reversed sense.

The hand shown in the drawings is a reproduction of a natural hand, pending normally from the arm. The member is suitably constructed of some light and plastic material, of sufficient strength to enable the same to conveniently perform the functions of a pair of pincers or a support, which may be considered as essential to the hand.

The particular positions of the fore and middle 45 fingers which provide for different degrees of

movement (Figure 1), facilitate gripping, without using excessive pressures, of the objects accommodated for that purpose by the right or existing hand, with the natural speediness conferred by long habit and which may be noticed with many people not accustomed to make ambidextrous use of their hands.

A suitable connection provided at the wrist causes the hand to adopt a position of reception or of petition, according to the necessities of the multiple movements required, while, when walking or standing about in the office or similar place, by a reverse movement, the hand will be caused to adopt a natural attitude, by resting on the abdomen.

The movements set forth and other movements hereinafter to be described, correspond to an attitude of support which by means of the jointed thumb in an open position and the little finger in its natural shape of a hook, will help to hold a glass or other object of a certain volume; the movements of a pair of pincers, executed by the jointed thumb relative to the forefinger which is fixed and of a somewhat curved shape, will provide for different degrees of progression between the ball of the thumb and the third phalanx of the index, between said ball and the second phalanx, between the second phalanx of the thumb and the phalanx of the index, and between the phalanx of the thumb and the hand, properly, in a descending progression till the joining of the thumb with the hand itself.

There also exist several different degrees of progression between the third phalanx of the index and the second phalanx of the middle finger, in a descendent progression until the joining of both the said fingers of the hand. Further degrees or gauges of separation exist between the middle and the fourth finger, also in a descendant progression till the joining of said two fingers, and a similar arrangement is found between the fourth finger and the index, and finally, a larger gauge of grip exists between the small finger and the hand. The pincer function is obtained by sliding, with the right hand, the object to be seized, between the fingers of the orthopedic hand, according to its thickness or volume.

Thus, by means of the above arrangement, the varying gauges or separations between the fingers and their several parts are obtained.

In the form of construction shown, 1 indicates the wrist block which by means of a screw 2 is threaded into the forearm, not shown in the drawings and which may be of any suitable type.

Said wrist is provided with a recess 3 which

contains the connecting device 4 which owing to the spring 5 and detent 6, may perform a slight movement, so as to project above the surface of the wrist.

Said connecting means allows of fixing or engaging the hand in certain positions by means of suitable cooperating devices, not shown, provided at, or applied to the desired part of the person's body, as by means of a girdle, or the like for example as shown in my copending application Serial No. 466,461.

The hand 7 is rotatably connected to the wrist by means of a guide element or spring stud 8 formed by a series of spring leaves with shoulders at their outer ends which engage behind a mating shoulder on the side wall of a socket formed in the wrist, so as to allow of an angular displacement of about 45°, preferably, by means of the pins 9, guided in slots 10 formed in the wrist.

Suitable hooks 11, placed at convenient points of the hand, permit of connecting the same as may be required, to a waist support or belt in a manner similar to that of the connecting device 4.

With reference now to the construction of the hand, it will be seen that the thumb 12 is jointed, the same as the fourth finger 15, while the index 13, middle finger 14 and small finger 16 are fixed. The jointed thumb 12, in cooperation with the fixed index, act in the manner of a pair of pincers.

The separating movement of the thumb with regard to the fixed index is performed by the action of a spring 17, secured to the pin 18. The movement in an opposite direction is controlled by a ratchet member 19, integral with the part 21, which is pivotally mounted on a pin 20 constituting an axis of rotation. The different positions of the thumb are controlled by the release member 22, which by means of the detent 23 and influenced by the energy transmitted thereto by the spring 24, arranged on its axis of rotation, is caused to engage with different teeth of the ratchet member 19, thereby establishing in a gradual and controlled manner the adjusted position which may be desired. By means of the button 25, the action of the release member 22 may be annulled and the thumb carried back to its original position by the action of the spring 17.

In Figures 5 and 6 the details of the joint of the fourth finger 15 are shown. This finger oscillates about the axle 26. An opening movement is transmitted to the finger by means of a spring 27, secured to the pin 28, and a cable 29 which extends from the upper end 30 of the phalanx. In a manner similar to the mechanism described in connection with the thumb, a rack member 31, pivoted on the pin 32 at the base of the phalanx and guided by the pin 33, controls by means of its teeth 34 and the release member 35, acted upon by the spring 36, the gradual approach or separation of the finger to and from the palm of the hand.

The button 37 operates in the same manner and performs the same function as the button 25 of the thumb.

The orthopedic hand above described, may be complemented, if desired, by a fitting indicated at 38 in Figure 7, which has for object to affix the hand to a table, desk, counter, etc.

Said fitting is secured to the wrist 1 by means

of a dog and clamp, while its attachment to the table or desk is brought about by a screw 40, provided, if desired, with a vacuum cup 42, for increasing its adherence, so that the table or desk will be held between the edge of the hand, conveniently provided with a roughened rubber pad 41, and the cup 42 of the screw 40.

In order to enable the said fitting to adapt itself to varying thicknesses, the part of the same 10 secured to the wrist consists of a yielding steel blade 43, which allows of imparting thereto the required movements and hold the hand in its resting position on the table or the like.

The object of fixing the hand by means of 15 the device just described, is to facilitate a number of attitudes and movements of the same in connection with working, eating or any other occupation which requires the hand to be held on the table, in a firm position.

An orthopedic hand, designed and constructed 20 as above set forth, may be used, with the natural assistance of the right hand, for performing a great number of functions of collaboration, such as the threading of a needle, sewing, holding a 25 glass, a working tool, shooting with a rifle, handling spectacles, doing shop work, performance of personal hygiene, holding of the reins when riding and numerous other uses, such as eating with both hands, which would be a convenient 30 form of using the improved hand.

The forms of construction set forth in the foregoing specification and shown in the accompanying drawings, are furnished by way of illustrative examples of the invention and it should be 35 clearly understood that the same is not restricted thereto, but that many modifications of shape, detail and construction may be introduced, without departing from the scope of this invention, such as will be clearly set forth in the following 40 claims.

Having now particularly described and ascertained the nature of my said invention and in what manner the same is to be performed, I declare that what I claim and desire to secure by 45 Letters Patent is:

1. An artificial hand, comprising, in combination a wrist block adapted for fixed connection with an artificial arm, a hand body, cooperating means on adjacent faces of the wrist block and hand body for rotatively connecting the same for limited angular movement; index, middle and small fingers integral with the hand body and a thumb and fourth finger pivotally and adjustably connected with the hand body, and a spring retracted eye member carried by the wrist block and adapted to be engaged with a support on the body of the user of the hand.

2. An artificial hand, comprising, in combination a wrist block adapted for fixed connection 60 with an artificial arm, a hand body, cooperating means on adjacent faces of the wrist block and hand body for rotatively connecting the same for limited angular movement; index, middle and small fingers integral with the hand body and a thumb and fourth finger pivotally and adjustably connected with the hand body, and a spring clamp carried by the wrist block for slidably connecting the hand to a table or the like, said clamp being of substantially U-shape and having one 65 end secured to the wrist block and the other end provided with securing means.

70 JOSE ANTONIO QUIRNO COSTA.
